US00D998420S

(12) **United States Design Patent** (10) Patent No.: **US D998,420 S**
(45) Date of Patent: **** Sep. 12, 2023**

(54) **BOTTLE WITH CLOSURE FOR AN APPLIANCE FOR PREPARING BEVERAGES**

(71) Applicant: **ISi GmbH**, Vienna (AT)

(72) Inventor: **Dominik Meier**, Munich (DE)

(**) Term: **15 Years**

(21) Appl. No.: **35/515,888**

(22) Filed: **Dec. 9, 2022**

(80) **Hague Agreement Data**

Int. Filing Date: **Dec. 9, 2022**

Int. Reg. No.: **DM/225740**

Int. Reg. Date: **Dec. 9, 2022**

Int. Reg. Pub. Date: **Dec. 30, 2022**

(30) **Foreign Application Priority Data**

Jun. 15, 2022 (AT) ..... Mu 21/2022
